UNITED STATES PATENT OFFICE.

IRVING L. HOTALING, OF RIVERTON, NEW JERSEY.

CURTAIN-FIXTURE.

No. 842,149.

Specification of Letters Patent.

Patented Jan. 22, 1907.

Application filed February 10, 1906. Serial No. 300,435.

To all whom it may concern:

Be it known that I, IRVING L. HOTALING, a citizen of the United States, residing at Riverton, in the county of Burlington and 5 State of New Jersey, have invented certain new and useful Improvements in Curtain-Fixtures, of which the following is a specification.

This invention relates to curtain-fixtures 10 of that type wherein a curtain-stick secured in or to the lower portion of a curtain is provided with a head at each end carrying devices engaging a guiding-groove of the window-frame and automatically resisting, 15 through frictional engagement with the guide, the upward pull of the curtain-roller spring, while permitting the curtain and fixture to be freely drawn downwardly.

The object of the present invention is to 20 provide a simple, economical, and efficient curtain-fixture; and to this end the invention comprises a device chiefly characterized by the provision of a curtain-stick and a head having a fixed pivotal connection to the 25 stick and an elastic bearing on the guide.

My invention will be readily understood when considered in connection with the accompanying drawings, showing preferred 30 embodiments thereof, wherein—

30 Figure 1 is a longitudinal sectional view of one end of a curtain-stick equipped with one form of my improved holding device. Fig. 2 is a similar view of the opposite end of a curtain-stick equipped with a similar device 35 provided with a roller instead of a friction-tip. Fig. 3 is a similar view showing a modified form of head and tip. Fig. 4 is a similar view illustrating a still further modified form of tip. Fig. 5 illustrates a double form of the 40 device, the two parts of which have a knuckle engagement with each other; and Fig. 6 illustrates a still further modification wherein the head is equipped with a pair of frictionally-retarded or brake rollers.

45 Referring to the drawings, 10 designates in all of the views an end portion of a tubular curtain-stick, such as is commonly carried in a pocket formed in and across the lower end of a spring-actuated curtain or shade, and 11 50 designates in all of the several views a bent leaf-spring, the inner free end of which bears against the bottom of the curtain-stick in a manner to force outwardly or toward the casing-guide the upright member of an L-shaped fixture-head that is pivotally mounted in the end of the curtain-stick, as

hereinafter more particularly described in connection with each of the several specific forms illustrated.

Referring to Fig. 1, 12 designates the head 60 in the form of an elbow or bell-crank lever, pivoted at 13 in the end of the curtain-stick 10, the inwardly-extending arm of said head having attached thereto the outer end of the leaf-spring 11, while the upwardly-extending 65 arm is provided on its outer face with a friction-pad 14, that is normally pressed by the spring 11 into engagement with the casing-guide, the pad-contacting surface of which is indicated at 15. In order to provide for a 70 limited angular play of the elbow-lever, the upper portion of the end of the curtain-stick 10 is slotted, as indicated at 16, to receive the upright arm of the lever, said slot extending inwardly a slight distance beyond 75 the inner edge of the arm.

Fig. 2 shows a construction generally similar to that of Fig. 1, the upright arm of the elbow-lever 12^a carrying a roller 17, this construction being suitable for curtains or 80 shades equipped with relatively light curtain-winding springs, wherein the outward thrust of the fixture-head against the guide caused by the spring 11 affords a sufficient resistance to the upward pull of the curtain-roller 85 spring to maintain the curtain stationary in any adjusted position.

In the form of the invention illustrated in Fig. 3 the upright arm of the elbow-lever 12^b is cored out, as indicated at 18, in which core 90 is placed a compression-spring 19, the upper end whereof bears frictionally against the periphery of a roller 20, mounted on a pin 21, carried by the upper end of the arm. Preferably and as herein shown the roller has an 95 enlarged or lost-motion bearing on its pivot-pin, which permits a frictional engagement of the periphery of the roller not only with the upper end of the spring, but also with the lower end of a vertical slot in the upper 100 end of the arm in which the roller is mounted, thus increasing the braking effect on the roller produced by the upward pull of the curtain induced by the curtain-roller spring.

Fig. 4 illustrates a form of the device 105 wherein the upright arm of the elbow-lever 12^c has non-rotatably mounted therein a bearing member 22, that is loosely surrounded by a ring 23, preferably of rubber or leather, producing a frictional engagement with the 110 periphery of the bearing member 22, thus affording a sufficient brake to the free rota-

tion of the ring 23 to resist the normal upward pull of the curtain.

Fig. 5 illustrates a modification of the invention involving a double form of the fixture-head previously described adapted to afford a contact of the head with the guide-groove both above and below the end of the curtain-stick. In this view the elbow-lever 12^d is provided just below its pivot with a depending tooth 24, that engages a notch 25 in the upper end of a depending companion lever 26, that is pivoted to the end of the curtain-stick at 27 and works in a slot 16^a in the lower portion of the curtain-stick. The outer free ends of the levers may be equipped with plain rollers 17^a or any other form of guide-contacting tip. It will be observed that in this form of the invention the action of the spring 11 is to throw the upright arm of the elbow-lever 12^d outwardly or toward the guide and that the tooth 24, engaging the notch 25 of the lower lever 26, at the same time imparts to the latter a similar outward movement toward the guide, thus maintaining both tips 17^a in engagement with the latter.

For the purpose of securing a longer and more extended bearing of the fixture-head on its guide the construction illustrated in Fig. 5 may be advantageously employed, wherein the elbow-lever 12^e is cored, as at 18^a, and provided with a compression-spring 19^a, the opposite ends of which bear frictionally upon the adjacent portions of the peripheries of a pair of guide-rollers 28 and 29, mounted on pins 30 and 31, respectively, in the upright arm of the lever, said spring exerting a braking effect upon both rollers and causing both to drag upon the surface of the guide contacted thereby. This construction and that of Fig. 5 are particularly useful in connection with very wide curtains requiring a long curtain-stick, since it tends to prevent canting of the latter when manipulated.

The operative principle of all the several forms of the invention shown is the same. The elastic or resilient inner or horizontal arm of the elbow-lever represented by the spring 11 always acts to force the upright arm of the lever and the fixture-tip carried thereby into engagement with the casing-guide with more or less friction, according to the form of tip employed, which will depend upon the degree of resistance necessary in the fixture to overcome the normal pull of the curtain-roller spring and hold the curtain

in adjusted position. At the same time the device affords but a slight resistance to the manual manipulation of the curtain-stick in a downward direction.

60

I claim—

1. A curtain-fixture comprising a curtain-stick, and an elbow-lever having substantially horizontal and vertical arms pivoted to the end of said stick, the horizontally-extending arm of said lever being elastic and bearing at its end on said stick, and the vertically-extending arm being adapted to bear at its end on a guide of the casing, substantially as described.

65

2. A curtain-fixture comprising a hollow curtain-stick, and an elbow-lever having inwardly and outwardly extending arms relatively to the stick pivoted in the end of said stick, the inwardly-extending arm of said lever being elastic and bearing upon the stick, and the outwardly-extending arm being adapted to contact a guide of the window-casing, substantially as described.

70

3. A curtain-fixture comprising a hollow curtain-stick, and an elbow-lever having inwardly and outwardly extending arms relatively to the stick pivoted in the end of said stick, the inwardly-extending arm of said lever terminating in a spring bearing upon the stick, and the outwardly-extending arm terminating in a friction-tip adapted to engage a guide of the casing, substantially as described.

75

4. A curtain-fixture comprising a curtain-stick, an elbow-lever pivoted to the end of the stick and having an inwardly-extending elastic arm bearing upon the stick, and an auxiliary lever pivoted to the same end of the stick and connected with said elbow-lever by a toothed connection, the outer ends of said levers being adapted to contact a guide of the casing, substantially as described.

80

5. A curtain-fixture comprising a hollow curtain-stick, an elbow-lever pivoted in the end of the stick and having an inwardly-extending spring-arm bearing upon the stick, and an auxiliary lever pivoted in the same end of the stick and connected with said elbow-lever by a toothed connection, the outer ends of said levers being adapted to contact a guide of the casing, substantially as described.
